Primary Examiner — Robert M Spear*Assistant Examiner* — Darcey E Heflin(74) *Attorney, Agent, or Firm* — Young & Thompson(57) **CLAIM**

The ornamental design for a thermal bottle lid, as shown and described.

DESCRIPTION

FIG. 1 is a front perspective view of a thermal bottle lid showing my new design;

FIG. 2 is a front view thereof; a rear view being a mirror image thereof;

FIG. 3 is a right side view thereof; a left side view being a mirror image thereof;

FIG. 4 is a top view thereof;

FIG. 5 is a bottom view thereof;

FIG. 6 is an enlarged view showing a square area of 6 at FIG. 2 thereof;

FIG. 7 is a bottom perspective view thereof;

FIG. 8 is an exploded view thereof; and,

FIG. 9 is a perspective view of the thermal bottle with lid. The broken lines represent the unclaimed portions of thermal bottle and form no part of the claimed design.
